CLAIM

The ornamental design for a dust bag, as shown and described.

DESCRIPTION

FIG. 1 is a front, left and top perspective view of a dust bag, showing my design.

FIG. 2 is a rear, right and bottom perspective view thereof.

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

FIG. 9 is an enlarged view of portion 9 shown in FIG. 1; and, FIG. 10 is an enlarged view of portion 10 shown in FIG. 2. The broken lines in the drawings illustrate the portions of the Dust bag, which form no part of the claimed design. The dot-dashed broken lines in the drawings indicate cutoff boundaries for the enlarged detailed portion views and form no part thereof.
